UNITED STATES PATENT OFFICE.

JOHN NAYLOR, OF FREEPORT, ILLINOIS.

FEED-BOILER AND WATER-HEATER.

SPECIFICATION forming part of Letters Patent No. 430,673, dated June 24, 1890.

Application filed January 12, 1889. Serial No. 296,149. (No model.)

To all whom it may concern:

Be it known that I, JOHN NAYLOR, a citizen of the United States, residing at Freeport, in the county of Stephenson and State of Illinois, have invented certain new and useful Improvements in Feed-Boilers and Water-Heaters; and I do declare the following to be a full, clear, and exact description of the invention, such as will enable others skilled in the art to which it appertains to make and use the same, reference being had to the accompanying drawing, and to the letters of reference marked thereon, which form a part of this specification.

My invention consists of a novel construction of feed-boiler and water-heater, which will be fully understood by the following description and claim.

The accompanying drawing is a vertical section of my improved feed-boiler and water-heater.

The feed-boiler D is provided with cover d, having the valve d' and handle d², and inserted into the fire-chamber or air-space B above the grate C. This fire-chamber has a draft b⁵ and a discharge-flue B'. Outside of the fire-chamber is a water vessel or heater A, provided with a heating-pipe E, which passes across the fire-chamber above the fire.

This pipe is fastened in the walls of the fire-chamber by means of nuts e and washers f, forming a tight joint. The water passes under the fire-chamber, which rests on supports a.

In the above arrangement the feed-boiler D is completely surrounded by the fire-chamber B and the water-chamber in turn completely surrounds the fire-chamber, so as to receive all of the external heat. The water-tube E being immediately above the fire-pit, receives the heat therefrom and also promotes the circulation of the water and heat throughout the peculiar-shaped heater.

Having described my invention, what I claim is—

The above-described combination of a feed-boiler D, surrounded by the fire-chamber B, having smoke-outlet B' at the top thereof, with the water-heater A surrounding the fire-chamber and smoke-passage, and the tube E above the fire-chamber, substantially as and for the purposes set forth.

In testimony whereof I affix my signature in presence of two witnesses.

JOHN NAYLOR.
